UNITED STATES PATENT OFFICE

IRVING C. JENNINGS, OF SOUTH NORWALK, CONNECTICUT

ROTARY PUMP

Application filed September 4, 1924, Serial No. 735,936. Renewed January 24, 1928.

The object of this invention is to improve that class of rotary pumps in which a liquid revolving in a casing is employed as the motivating agent.

5 The invention will be best understood in connection with the accompanying three sheets of drawings forming part of this application for patent, and in which

Fig. 1 is a cross-sectional elevation of a pump constructed to contain my improvements, the section being taken on the line 1—1 of Fig. 2;

Fig. 2 is a cross-section taken on the line 2—2 of Fig. 1;

15 Fig. 3 is an end elevation partly in section of the rotor;

Fig. 4 is a plan of the rotor;

Fig. 5 is a cross-sectional view of the rotor on the line 5—5 of Fig. 3;

20 Fig. 6 is a diagram or a development of the lobes;

Fig. 7 is a sectional view illustrating the commercial form of pump which I have aimed to improve;

25 Fig. 8 is a diagrammatic sectional view taken on the line 8—8 of Fig. 1, showing the action of the rotor; and

Fig. 9 is a similar view taken on the line 9—9 of Fig. 1.

30 The particular purpose of my invention is to improve the rotary pump shown, described and claimed in U. S. Letters Patent granted to Lewis H. Nash, No. 953,222, dated March 29, 1910 and No. 1,091,529, dated March 31, 1914.

The pump shown in these patents briefly consists of an eccentric casing, that is, a casing the inside of which is eccentrically arranged relatively to the axis of the rotor, 40 a rotor revolving in said casing having buckets or peripheral displacement chambers, and suitable ports for allowing the fluid to be pumped to enter and leave said displacement chambers. The pump casing is partly filled 45 with liquid, and when the rotor is revolved, it will whirl this liquid around inside of the pump casing so that the centrifugal force and inertia of the liquid will cause it to follow the contour of the casing, whereby the 50 liquid will enter and recede from each dis-

placement chamber and act in effect as a liquid piston therein. In said patents, that part of the eccentric casing which recedes from the rotor is called a lobe and as shown in said Patent No. 1,091,529, the casing may 55 be shaped to have one or a plurality of lobes.

The Nash pump as covered by said patents and as developed in practice has usually consisted of an elliptical shaped casing having two lobes so that the liquid will enter 60 and recede from each displacement chamber twice for each complete revolution of the rotor. The blades or partitions which form the displacement chambers are shown in

said patent as radial or straight, but in actual practice the outer ends thereof usually have been set at a forward angle so as to hook the liquid into the chambers and to assist in its entrance thereto. This commercial form of the Nash pump is shown in 65

diagram in Fig. 7, wherein in the sectors A and B, the liquid is shown as leaving the displacement chambers and the fluid to be pumped as being drawn into the same; and whereas in sectors C and D the liquid is 70

shown as being forced into the displacement chambers and the fluid to be pumped as being forced out of the same. It will be noticed, that the outer ends of the blades are 75

forwardly inclined so as to hook in the liquid into the displacement chambers in sectors C and D. This is advantageous in that it helps the flow of the liquid into the 80

chambers and lessens hydraulic shock. This construction is disadvantageous, however, when the blades work in the sectors A and 85

B, as then the liquid has to be thrown out of the displacement chambers and the shape of the blades is such as to retard this action. If the blades could be backwardly inclined, 90

when they act in the sectors A and D, the powerful throwing out action obtained in an ordinary centrifugal liquid pump could be obtained and the efficiency of the pump 95 could be very much increased.

The principal object of my invention is to obtain this desirable effect and at the same time preserve the desirable hooking effect of the forwardly inclined blades.

To this end, my invention consists in 100

- forming such a rotor or rotors with the blades in part at a forward angle and in part at a back angle, and in arranging the lobe or lobes properly to co-act therewith so that the desirable hooking in action will be obtained when the liquid is to enter the displacement chambers and the desirable centrifugal action will be obtained when the liquid is to leave the displacement chambers. 5
- 10 The details of the invention will be best understood by a detailed description of the drawings. Referring to the drawings and in detail, 10 designates an inlet shell or casing to which the inlet pipe 11 for the fluid to be pumped is attached, and 12 designates an outlet shell or casing to which the outlet pipe 13 for the fluid to be pumped is attached. The casings 10 and 12 are substantially similar except that they are rights 15 and lefts. 14 designates a central ring or casing, which contains the eccentric lobe or lobes. The structure may be secured together by bolting the flanges on the casings 10 and 12 to the ring 14 and these parts may 20 have suitable supporting feet. The central parts of the casings 10 and 12 are shaped to form bearings 15—15 to which oil passages 16—16 may run. Spiders or flanges 17—17 are secured to the outer sides of the casings 25 30 10 and 12 and these spiders carry bearings 18—18 for the rotor shaft 19, which is journaled in the same and in the bearings 15—15 previously referred to. The bearings 18—18 may be ball or any other suitable 35 form of bearing. Stuffing boxes 20—20 are preferably arranged at the outer ends of the bearings 15—15, so as to prevent any liquid leaking out of the sides of the casings 10 and 12.
- 40 R designates the rotor, which is keyed or secured on the central part of the shaft 19, and which rotor fits tightly in the annular space between the two casings 10 and 12 and the ring 14.
- 45 The rotor has a central flange 21 and two side flanges 22 and 23. Blades or partitions 24 are arranged between the central partition 21 and the side partition 22 and these blades are formed or set at a forward angle 50 so that they will hook into the liquid and obtain the hooking action previously described. Blades 25 are arranged between the central partition or flange 21 and the side partition 23. These blades 25 are set 55 at a back angle so as to obtain the desirable centrifugal action or throw out of the liquid previously described. Holes 26 are formed in the central partition 21 whereby each displacement chamber will be formed by the 60 space included between the two side flanges 22 and 23 and two adjacent forwardly extending blades 24 and the two adjacent backwardly extending blades 25. Thus, there are two sets of blades around the periphery of the wheel, one set 24 having its 65 blades forwardly inclined and the other set 25 having its blades backwardly inclined. In other words, each displacement chamber has a set of blades forwardly inclined and a set of blades backwardly inclined. The lobes L in the ring 14 are made substantially 70 half width of the rotor or of a width equal to one set of blades and are staggered or offset axially, so that the forwardly inclined blades 24 only will co-operate with a lobe, when liquid is to be hooked into the displacement chambers, and so that the rearwardly inclined blades 25 only will co-operate with a lobe when liquid is to be thrown out from the displacement chambers. The 75 distance which each lobe is staggered is such as to bring the lobes into proper position to obtain this effect. A development or unrolling of the lobes is shown in Fig. 6. 80
- If desired, thin plates V may be placed 85 over the laterally extending part of the lobes to prevent the blades 24 and 25 both acting at the same time, if it is desired to prevent any eddies or unnecessary hydraulic friction in the displacement chambers. 90
- Suitable inlet and outlet ports P—P and P'—P' for the entrance and exit of the fluid to be pumped into and from the displacement chambers are formed in the shells 10 and 12. 95
- The action of the pump can be understood by referring to Figs. 8 and 9. It is to be noticed in the first place that the rotor will throw the liquid in the ring 14 around with the same so that it will follow the path of the lobes. Fig. 8 is a sectional view which shows the action of the backwardly inclined blades 25. It will be seen that in the sectors A and B, the liquid will be thrown out of the displacement chambers by centrifugal 100 action, thus creating a powerful suction in the displacement chambers which will draw the fluid to be pumped into the displacement chambers through the ports P. It will be seen that when the blades 25 turn in the sectors C and D, no action either of entrance or exit from the chambers can take place through these blades as the ends of the same then will fit closely to the inside of the ring. 105
- Fig. 9 designates a section through the forwardly extending or hook in blades 24. It will be seen that these blades, when they are in the sectors C and D, will take or hook the liquid into the displacement chambers and thus will force the fluid to be pumped 110 out through the outlet ports P'. It will be seen that when the blades 24 are in the sectors A and B they will do no work as the liquid cannot enter or leave the same as the blades then will fit close to the inside of the ring 14. 115
- Thus it will be seen that the entrance of the liquid into the displacement chambers is obtained with a hooking action, that the liquid will flow laterally in the displacement 120 chambers and thus will be pumped out through the outlet ports P'. 125
- 130

chambers and that the liquid will be forced out from the chambers with a centrifugal throw out action.

It will be seen that the fluid to be pumped also is hooked into the displacement chambers without shock, due to the fact that the parts of the blades, viz. the internal ends thereof, which co-operate with the entrance port or ports $P-P'$ are set at a forward angle relatively to said entrance port or ports, as shown in sectors A and B of Fig. 8; and that the fluid to be pumped leaves the displacement chambers with a low velocity relatively to the exit port or ports $P'-P'$, and with a minimum of shock due to the fact that the parts of the blades which co-operate with the said exit port or ports $P'-P'$, viz. the internal ends thereof, are set at a backward angle relatively to said exit port or ports $P'-P'$ as shown in sectors C and D of Fig. 9.

These points are of particular advantage when the fluid to be pumped consists in whole or in part of a liquid.

When the pump is to be used as a gas pump, the supply of displacement liquid can be maintained by the small pipe 30 connected to the inlet pipe 11 as shown in Fig. 1.

I have shown the ports as connecting to the bottom of the displacement chambers as this arrangement seems most advantageous in connection with my improvement. The ports, however, could be sidewise arranged as in the Nash pump previously referred to, if desired.

By using a plurality of staggered lobes arranged as shown in Fig. 6 an advantageous balancing effect is obtained. That is to say, the pressures and strains on the rotor in segments A and B will balance each other and particularly the pressure and strains on the rotor in segments C and D where the liquid is forced into the displacement chambers will balance each other and hence a very smooth action is obtained.

By these arrangements the efficiency of the pump can be greatly increased. While water is ordinarily used as the displacing liquid because of the fact that it is usually available and because of the higher efficiency due to its viscosity and relatively great weight, any other liquid may be employed provided it does not form scale or attack the interior of the pump and provided it is not too viscous to operate.

The fluid to be pumped may be air or any other gas or any liquid or any compound gas and liquid. The pump may be used as a suction pump, as a pressure pump, or, as a pump utilizing both its suction and pressure effects.

As practically all hydraulic shock is eliminated the pump can be run at high speed and great efficiencies and higher pressures and vacuums can be obtained.

The details and arrangements herein shown and described may be greatly varied by a skilled mechanic without departing from the scope of the invention as expressed in the claims.

Having thus fully described my invention, what I claim and desire to secure by Letters Patent is:—

1. In a rotary pump employing a liquid as the motivating agent, the combination of an eccentric casing, a rotor therein having blades or partitions forming peripheral buckets or displacement chambers, certain of the blades being set at a backward angle to obtain a centrifugal effect and certain of the blades being set so as not to obtain a centrifugal effect and suitable ports for allowing the fluid to be pumped to enter and leave said displacement chambers.

2. In a rotary pump employing a liquid as the motivating agent, the combination of a rotor or rotors having displacement chambers formed by blades set at a forward angle and by blades set at a back angle, and suitable ports for the entrance and exit of the fluid to be pumped.

3. In a rotary pump employing a liquid as the motivating agent, the combination of a casing having a lobe, a rotor therein having blades or partitions forming peripheral buckets or displacement chambers, certain of the blades being formed at a forward angle and certain at a back angle, and suitable ports for allowing the fluid to be pumped to enter and leave said displacement chambers.

4. In a rotary pump employing a liquid as the motivating agent, the combination of an eccentric casing, a rotor having two sets of blades or partitions forming peripheral buckets or displacement chambers, one set of blades being forwardly inclined and the other set of blades being backwardly inclined, and suitable ports for allowing the fluid to be pumped to enter and leave said displacement chambers.

5. In a rotary pump employing a liquid as the motivating agent, the combination of an eccentric casing, a rotor having two sets of blades or partitions arranged side by side and forming peripheral buckets or displacement chambers, one set of blades being forwardly inclined and the other set of blades being backwardly inclined, and suitable ports for allowing the fluid to be pumped to enter and leave said displacement chambers.

6. In a rotary pump employing a liquid as the motivating agent, the combination of an eccentric casing, a rotor therein having displacement chambers formed by blades or partitions, and suitable ports for the entrance and exit of the fluid to be pumped, the parts of the blades which co-operate with the entrance port or ports being set at

a backward angle relatively to said entrance port or ports only.

7. In a rotary pump employing a liquid as the motivating agent, the combination of an eccentric casing, a rotor therein having displacement chambers formed by blades or partitions, and suitable ports for the entrance and exit of the fluid to be pumped, the parts of the blades which co-operate with the exit port or ports being set at a forward angle relatively to said exit port or ports only.

8. In a rotary pump employing a liquid as the motivating agent, the combination of an eccentric casing, a rotor therein having displacement chambers formed by blades or partitions, and suitable ports for the entrance and exit of the fluid to be pumped, the blades which co-operate with the entrance port or ports being set at a backward angle relatively to said entrance port or ports and the blades which co-operate with the exit port or ports being set at a forward angle relatively to said exit port or ports.

9. In a rotary pump employing a liquid as the motivating agent, the combination of a casing, a rotor having two sets of blades or partitions forming peripheral buckets or displacement chambers, one set of blades being forwardly inclined and the other set backwardly inclined, suitable ports for allowing the fluid to be pumped to enter and leave said displacement chambers, and a staggered lobe in the casing with which the blades cooperate.

10. In a rotary pump employing a liquid as the motivating agent, the combination of a casing, a rotor having two sets of blades or partitions forming peripheral buckets or displacement chambers, one set of blades being forwardly inclined and the other set backwardly inclined, suitable ports for allowing the fluid to be pumped to enter and leave said displacement chambers, and a plurality of staggered lobes in the casing with which the blades cooperate.

11. In a rotary pump employing a liquid as the motivating agent, the combination of a casing, a rotor having two sets of blades arranged side by side forming peripheral buckets or displacement chambers, one set of blades being forwardly inclined and the other set of blades being backwardly inclined, suitable ports for allowing the fluid to be pumped to enter and leave said displacement chambers, and a staggered lobe in the casing of a width substantially equal to that of one set of blades with which the blades cooperate.

12. In a rotary pump employing a liquid as the motivating agent, the combination of a casing, a rotor having two sets of blades arranged side by side forming peripheral buckets or displacement chambers, one set

of blades being forwardly inclined and the other set of blades being backwardly inclined, suitable ports for allowing the fluid to be pumped to enter and leave said displacement chambers, and a plurality of staggered lobes in the casing, each of a width substantially equal to that of one set of blades with which the blades cooperate.

13. In a rotary pump employing a liquid as the motivating agent, the combination of an eccentric casing, a rotor therein having side and middle partitions, forwardly inclined blades between the middle and one side partition and backwardly inclined blades between the middle and the other side partition, and holes through the central partition, whereby displacement chambers will be formed on said rotor having forwardly inclined blades and backwardly inclined blades, and suitable ports for allowing the fluid to be pumped to enter and leave said displacement chambers.

14. In a rotary pump employing a liquid as the motivating agent, the combination of an eccentric casing, a rotor therein having side and middle partitions, forwardly inclined blades between the middle and one side partition and backwardly inclined blades between the middle and the other side partition, and holes through the central partition, whereby displacement chambers will be formed on said rotor having forwardly inclined blades and backwardly inclined blades, the bottom of said chambers being open, and suitable inlet ports for allowing the fluid to be pumped to enter and leave said displacement chambers at the bottom thereof.

15. In a rotary pump employing a liquid as the motivating agent, the combination of an inlet shell, an outlet shell, a ring between the shells, an eccentric staggered lobe or lobes in said ring, a rotor fitted in the annular space between said shells and said ring having blades or partitions forming peripheral buckets or displacement chambers, certain of the blades being formed at a forward angle and certain at a back angle, and suitable ports for allowing the fluid to be pumped to enter the rotor from the inlet shell and to leave the rotor and pass into the outlet shell.

16. In a rotary pump employing a liquid as the motivating agent, the combination of an eccentric casing having a staggered lobe or lobes, a rotor therein having blades or partitions forming peripheral buckets or displacement chambers, certain of the blades being formed at a forward angle and certain at a back angle, a plate or plates over the central part of the lobe or lobes to prevent eddy in the displacement chambers, and suitable ports for allowing the fluid to be pumped to enter and leave said displacement chambers.

17. In a rotary pump employing a liquid as the motivating agent, the combination of an eccentric casing, a rotor therein having blades or partitions forming peripheral buckets or displacement chambers, certain of the blades being set at a forward angle to obtain a hook-in effect, and certain of the blades being set so as not to obtain a hook-in effect, and suitable ports for allowing the fluid to be pumped to enter and leave said displacement chambers.
